UNITED STATES PATENT OFFICE.

JOHN M. JOY, OF NEW YORK, N. Y., ASSIGNOR TO PAGE MACHINE COMPANY, OF NEW YORK, N. Y., A CORPORATION OF NEW YORK.

METHOD OF OPERATING PRINTING-TELEGRAPH RECEIVERS.

SPECIFICATION forming part of Letters Patent No. 780,663, dated January 24, 1905.

Application filed August 1, 1902. Serial No. 117,995.

To all whom it may concern:

Be it known that I, JOHN M. JOY, a citizen of the United States, residing in the city, county, and State of New York, have invented certain 5 new and useful Improvements in Methods of Operating Printing-Telegraph Receivers, of which the following is a specification.

My invention relates, broadly, to a method of operating electrical apparatus, such as the 10 apparatus used for actuating the mechanism of a printing-telegraph receiver, although the method may be used in connection with any class of apparatus to which it is applicable.

The object of my invention is to increase 15 the rate of speed at which a printing-telegraph receiver or other like apparatus may be worked with a minimum of power and high efficiency.

Further objects of my invention will herein-after appear; and to these ends my invention 20 consists in the method of operating electrical apparatus, substantially as hereinafter fully set forth in this specification, suitable apparatus for carrying out my method being illustrated in the accompanying drawing, which 25 represent diagrammatically a sending and a receiving station with circuits and apparatus for operating a printing-telegraph receiver.

While many different kinds of apparatus 30 may be provided for carrying out my im- proved method of operation, I have chosen to illustrate diagrammatically apparatus for carrying out my invention such as shown and described in my copending application, Serial No. 118,524, filed August 5, 1902, and entitled 35 "Improvements in printing-telegraph receivers," for I have shown the apparatus in the aforesaid application as operated by the method herein described, although the method has not therein been claimed.

Since the mechanical construction of the 40 printing-telegraph receiver forms no part of my present invention, I have illustrated the parts in diagrammatic relation, with sufficient of the apparatus only shown to enable my 45 present invention to be understood.

Referring to the drawing, X represents a sending-station, and Y a receiving-station, with suitable circuits and apparatus connecting the two for transmitting messages and for re-

cording them according to my invention. At 5c the sending-station any suitable form of apparatus may be provided for transmitting impulses over the line, while at the receiving-station Y a printing-telegraph receiver is located, preferably of substantially the same 55 construction and having the general mode of operation as that described in my application above referred to, wherein polarized electro-magnetic apparatus is provided for controlling the operation of the type-wheel, while 60 unpolarized apparatus is provided for controlling the operation of the mechanism for printing the character selected and for controlling the paper-feeding mechanism. Circuits are shown having a number of receivers connect- 65 ed to distributing bus-bars or mains α α , and in the diagrammatic representation of apparatus at the receiving-station Y the escapement-lever 131 is actuated by means of a polarized 70 relay comprising the magnets 151, 152, 153, 70 and 154, the circuits of which are diagrammatically shown. Means are provided for polarizing the cores of these magnets, as shown the coils 151 and 152 being used for this purpose, while alternating currents or im- 75 pulses of different signs are sent through the coils 153 154, alternately strengthening one core and weakening the other, and thereby 80 vibrating the escapement-lever 131, thus allowing rotation of the escapement-wheel 130 for 80 selecting the desired characters or space on the type-wheel 7. The magnet 201 is also included in the circuit of the coils 153 154 for a 85 purpose hereinafter to appear.

In the diagram M, denotes a suitable motor 85 connected to the shaft 133, from which the power for actuating the mechanism of the receiver is derived, while A is a suitable source of electric energy for the motor, represented as a storage battery. A circuit includ- 90 ing coils 151 and 152 and a switch 200, controlled by magnet 201, is also derived from the battery A, and said coils 151 and 152 are so wound that the cores 155 and 156 are polarized with the oppositely-arranged poles of 95 the same sign, as indicated by the letters S S and N N in the diagram. The coils 153 and 154 are then so wound that upon passing a

positive impulse through them the magnetism of one of the cores, as 155, will be strengthened, while that of the other, as 156, will be neutralized, and then upon passing a negative impulse through these coils the magnetism of core 156 will be strengthened, while that of core 155 will be neutralized, and thus the escapement-lever 131 will be attracted to one side or the other, according to the character of the impulse transmitted over the line. Each character to be printed being selected by impulses sent over the line, the letter-selecting escapement-wheel may be moved to any desired position, and then the printing and feeding of the type-wheel may take place or the traverse position of the type-wheel may be changed, as desired, or the paper may be fed.

Referring more particularly to the drawing, suitable means are shown at B of any ordinary or usual character for determining the number of alternations in the current sent over the line, and, as shown, a common form of pin-cylinder 157 is provided, with 25 thirty-eight pins arranged on a shaft 158, which by any suitable means tends to rotate, but is held therefrom by controlling-levers 159, corresponding to the characters on the type-wheel, but one of which levers is shown. 30 A driving-pulley 160 may be connected with a suitable source of power for operating the pin-cylinder 157, and a friction-clutch 161 is shown in this instance between the gearing connected to the driving-pulley 160 and the 35 pin-cylinder shaft 158, so that the driving-pulley may at times rotate with the driving pin-cylinder. I also provide a shaft 163, which may be driven by any suitable power and, as shown, is connected to be driven from the driving-pulley 160, and I have shown it 40 connected therewith by a friction-clutch 162. Said shaft 163 carries an escapement-wheel 164, controlled by an escapement-lever 165, adapted to be actuated by a magnet 166, and 45 also upon the shaft 163 is arranged a commutator 167, with brushes 168 169 bearing thereon connected in circuit with a generator C, which generator is also connected with brushes 170, bearing upon a commutator 171. In this 50 instance a switch 203 is shown included in the circuit of the generator C, while another generator, 204, is adapted to be connected in series with generator C or cut out of circuit. The generator C in this instance is a direct- 55 current machine and supplies current for actuating the polarized magnets controlling the operation of the letter-selecting escapement 81, the direct current being commutated at the commutator 171 into alternating positive 60 and negative impulses and passing from the commutator by brushes 172 to the distributing-line *a a*, from which connection is made, as by the leads *b b*, to coils 153 and 154 of the polarized relays connected to actuate the escapement-lever 131.

Means are provided for rotating the commutator 171, as shown a connection being made through gearing to the pin-cylinder shaft 158, and any suitable form of commutator may be provided, it only being necessary 70 that as the commutator rotates with the brushes 170 and 172 bearing thereon the direct current from the generator C shall be transformed into alternating impulses. The number of these impulses is controlled at will by 75 means of the levers 159, and means are provided for automatically printing each character after it has been selected, and this is accomplished by means of the printing-magnets or controlling-magnets 96 and the mechanism 80 which they control. After the character desired to be printed has been selected and is in position to have an impression taken therefrom the circuits and apparatus are so arranged that the printing or controlling magnets 96 become operatively energized, thereby 85 affecting the armature 97, actuating the escapement-lever 93, withdrawing the pawl 173 from engagement with the tooth 174 on the escapement-wheel 70, and allowing said escapement- 90 wheel to rotate in the direction of the arrow until the tooth 175 comes into engagement with a pawl 176 on the other side of the escapement-lever 93. It will thus be seen that the tooth 177 on the escapement-wheel 70 is about in 95 readiness to engage the pawl 173 when the magnets 96 become deenergized after the printing has taken place.

Suitable means are provided, as shown in the application above referred to, for feeding the 100 type-wheel; but this means has not been illustrated in the present case, and, furthermore, as the figure is but a diagrammatic representation of one means of carrying out my invention the apparatus has been much simplified for the 105 sake of clearness, and in this connection any suitable means are shown for causing the printing-platen to strike the type-wheel 7. In this instance a bell-crank lever 178, pivoted at 179, is adapted to be actuated by pins or stops 180, 110 connected to the escapement-wheel 70. As the alternating impulses traverse the circuits connected with the generator C, the switch 203 being in the position shown in the drawings, magnets 153 and 154 are operated by means 115 of such impulses to actuate the escapement-lever 131, the printing or controlling magnets 96, which are unpolarized, are not operatively energized by the alternating current, and, as shown, they are so connected in the shunt as 120 to receive the alternations in the line. While the printing or controlling magnets 96 may be connected in the circuit in any desired manner, they are preferably connected in shunt to the line, since with this arrangement the controlling-magnets may be constructed to have a 125 greater impedance than that of the coils 153 and 154 in the main circuit. This arrangement causes the greater portion of the alternating current to traverse the circuits in the 130

magnets 153 and 154 rather than that of the controlling or printing magnets 96. Other advantages are gained by this arrangement of circuits, which will hereinafter appear. The 5 magnet 166, controlling the escapement-lever 165, is also not operatively energized by alternating currents passing through its circuit *d d*, shown as connected in shunt to the main line. As soon as the pin-cylinder 157 comes to rest 10 with the desired character on the type-wheel selected and in position to be printed a constant current will momentarily flow from the generator C through suitable resistances R R and through commutator 171 to the magnet 15 166, energizing said magnet and causing it to attract its armature, thereby releasing the escapement-wheel 164 and allowing it to rotate through half a revolution, thereby causing the conducting portions 181 on the commutator 167 to pass momentarily beneath the brushes 168 and 169, thus short-circuiting the resistances R R for an instant of time and allowing more direct current to momentarily flow from the generator C to and through the 20 commutator 171 to the line *a a*, energizing the printing or controlling magnets 96 sufficiently to cause them to attract the armature 97. This increase of current which caused the magnet 96 to attract the armature 97 was 25 but momentary in order to provide sufficient magnetism to attract the armature 97 against its spring, and then the normal strength of the current passing from the generator C to resistance R R is sufficient to hold said armature 97 in a retracted position as long as desired. By arranging the controlling-magnets 96 in a shunt to the line and in shunt to the escapement-magnets and making the controlling-magnets of less resistance than those controlling the escapement, but of greater impedance, more direct current will flow through the controlling-magnets, which is to be desired. 30 Suitable means are provided for deenergizing a circuit of the battery A, and thus prevent the operation of the receiver as long as desired. The means thus provided are preferably controlled from a distance, as at the transmitting-station X, and to these ends the 35 magnet 201 and switch 200 are included in the operating-circuits at the receiver, while the generator 204 is arranged to be switched into circuit at the transmitting-station and momentarily increase the tension of the line to 40 operate the magnet 201. The magnet 201 may be included in any suitable portion of the receiving-circuits; but as shown it is included in series with coils 153 and 154 and in shunt to the printing-magnet 96. Switch-magnet 201 is so designed and adjusted that 45 it will not become sufficiently energized to actuate its armature 205 under the ordinary working condition of the circuits, and means are provided for "boosting" the line when 50 desired in order to actuate switch-magnet 201.

For this purpose the additional generator 204 is provided at the transmitting-station, for by throwing the switch 203 from contact 206 to contact 207 generator 204 may be included in series with generator C, and thus raise the 70 potential of the lines sufficiently to cause magnet 201 to become energized and actuate its armature 205. This armature 205 is shown as one arm of a bell-crank lever 208, pivoted at 209 and having at its other end a cross-piece 210, provided with stops 211, while pivoted at 214 is a "flier" or arm 213, provided with a stop 218 and connected to move with a pinion 215, meshing with a gear 216, to which the switch 200 is connected. Contacts 217 coöperate with the switch 200, and to these contacts are connected wires leading from the battery A, so that the switch 200 is in series with the battery. The object of these mechanical and electrical connections is 80 to enable the battery-circuit to be broken when desired; but other suitable means may be substituted for those illustrated without departing from the spirit of my invention. 85

The shaft to which the switch 200 is connected is provided with a pinion 220, meshing with a gear 221 upon a winding-stem 222, from which the switch mechanism is actuated when released by the arm or flier 213. Upon lever 208 being actuated to release stop 218 from stop 211 the arm 213 will make nearly one revolution under the influence of the spring-actuated gearing connected thereto and it will be brought to a stop again against stop 212. The gear 217 will have been 90 rotated through nearly one whole revolution to break the circuit at switch 200. By moving the switch 203 to the position shown in the drawings the high-potential current sent to the line is reduced, reducing the operative current sent through magnet 201, so that by thus deenergizing magnet 201 and releasing armature 205 the stop 218 will be released from stop 212 and brought against stop 211, thereby allowing the arm 213 to complete a full revolution and complete the circuit at the switch 200. This brings the potential of the line 95 back to normal. The switch 200 is used simply to connect and disconnect the battery A of the receiving instrument into and out of operative circuit, so that battery-power can be saved when the receiving instrument is out of operation for any continued length of time. 100

Obviously some features of my invention may be used without others, and my invention 105 may be embodied in widely-varying forms.

Therefore without enumerating equivalents nor limiting myself to the construction shown and described, I claim, and desire to obtain by Letters Patent, the following:

1. The method substantially as herein described of operating a printing-telegraph receiver, which consists in transmitting impulses of alternating current to said receiver for selecting a character to be printed, transmitting 110

a direct current over the line, automatically momentarily increasing the line-potential for printing the character selected, and then automatically reducing the line-potential again 5 to normal strength.

2. The method substantially as herein described of operating a printing-telegraph receiver, which consists in transmitting alternating current over the line for selecting the 10 characters to be printed, then changing from alternating current to direct current, and automatically increasing the normal strength of said direct current momentarily to cause the printing of the character selected.

15 3. The method substantially as herein described of operating a printing-telegraph receiver, which consists in transmitting impulses of alternating current to the receiver for selecting the characters to be printed, preventing 20 the printing until desired by means of impedance, transmitting over the line a direct current of insufficient strength to cause the

printing of the character selected, and then momentarily increasing the line-potential to cause the printing of said character.

4. The method substantially as herein described of operating a printing-telegraph receiver, which consists in transmitting impulses of alternating current to the receiver for selecting the characters to be printed, transmitting over the line a direct current of insufficient strength to cause the printing of the character selected, automatically momentarily increasing the line-potential to cause the printing of said character, and then automatically 30 reducing the line-potential to normal strength.

In testimony whereof I have signed my name to this specification in the presence of two subscribing witnesses.

JOHN M. JOY.
